UNITED STATES PATENT OFFICE.

WILLIAM LOVE, OF BRYN MAWR, PENNSYLVANIA.

SINK.

SPECIFICATION forming part of Letters Patent No. 595,544, dated December 14, 1897.

Application filed April 14, 1897. Serial No. 632,177. (No model.)

To all whom it may concern:

Be it known that I, WILLIAM LOVE, a citizen of the United States, residing at Bryn Mawr, in the county of Montgomery and State 5 of Pennsylvania, have invented a certain new and useful Improvement in Sinks, of which the following is a specification.

My invention relates to a new and useful improvement in sinks, and has for its object 10 to cast in a single piece a sink and the back thereof and to provide means for the ready cleaning of both the waste-pipe and overflow and also to overcome the disadvantage which has heretofore existed in devices 15 of this description from offsets and projections which afford a shelter for various kinds of insects, such as roaches; and a further object of my improvement is to so cast the sink and back as to preclude the possibility of the 20 leakage from the spigots gaining access to the outside of the sink, and incidentally my improvement facilitates its securement in place, as well as the removal of any portion of the connecting-pipe for repair or renewal.

With these ends in view this invention consists in the details of construction and combination of elements hereinafter set forth and then specifically designated by the claims.

In order that those skilled in the art to 30 which this invention appertains may understand how to make and use the same, the construction and operation will now be described in detail, referring to the accompanying drawings, forming a part of this specification, in

which—

Figure 1 is a perspective view of my improvement when in place; Fig. 2, a vertical section thereof; Fig. 3, an enlarged cross - section showing the arrangement of the waste-pipe 40 and overflow; Fig. 4, an enlarged section of the coupling, and Fig. 5 a front view of the three-way coupling.

In carrying out my invention as here embodied I form the sink proper, A, with the back B by casting, and I prefer that this back shall stand at right angles to the body of the sink and have no projection upon its rear surface in order that it may be secured to a wall or wainscoting and when so secured will serve to support the sink with or without the use of legs or brackets.

In casting the back has formed thereon

casing-pipes C to receive the water-pipes D, and these casings are cut away from the back at the top, thereby producing a shoulder, and 55 couplings E, having flat rear walls E², are fitted over the upper ends of said casings and have downwardly - projecting flanges E³ formed thereon, which inclose the tops of the casings. The upper ends of said casings abut 60 shoulders formed along the bosses at the front of the couplings. These couplings are three-way, the upper and lower openings to which are threaded for the reception of the water-pipes, or in case a pipe does not lead from the 65 upper portion of the coupling then the opening therein may be closed by a fancy screw-plug E'. The water-pipes D are passed within the casing-pipes C from their upper open ends prior to placing the couplings E in place, 70 and afterward these pipes are threaded into the lower openings in the couplings, thereby not only securing the couplings in place, but also connecting the pipes thereto. The horizontal openings in the couplings are for the 75 reception of the threaded shanks of the spigots F, and when a hot-water apparatus is used instead of the plugs E' the pipes which lead to and from the boiler are threaded in the upper openings of the couplings. By this 80 arrangement it will be seen that all parts of the piping and joints therefor are so completely closed and surrounded as to prevent access thereto of insects or the accumulation of dirt, which is of considerable importance 85 from a sanitary point of view.

The waste-pipe G is secured to the trap H by being threaded in the lower end thereof, and this trap is preferably cast with the sink, in order that there may be no holes necessary 90 for the passage of bolts, thus avoiding an occasion for leakage, which often occurs in sinks as now constructed. Within the trap is formed an annular shoulder, upon which the screen I rests, and this screen is so arranged that it may be readily removed from the washer for cleaning purposes and in order that the pipe of a force-pump may be placed 95 within the waste-pipe when occasion requires.

The overflow-pipe J is cast with the body 100 of the sink and leads downward and inward and enters the trap, while a clean-out L is formed therein having internal threads for the reception of the threaded plug M, which

may be readily removed and by means of which a wire or other implement may be passed into the pipe K in either direction for cleaning the same.

5 In order that free access may be had to the overflow-outlet and the pipe connected therewith, the screen O is hinged over said outlet and adapted to be swung upward out of the way when access is to be had to the overflow. 10 In practice I prefer that a plug P may be adapted for fitting within the waste-pipe outlet in order that the sink may be used instead of the usual tin pan for dish-washing, since when this plug is in place water may be 15 accumulated within the sink to the level of the overflow. When the supply-pipes are to be connected with a hot-water boiler, either or both of the plugs E' may be removed from the housings and the pipes leading to and 20 from the boiler connected at this point with the supply-pipes and valves placed within said pipes, so as to control the flow of the hot water throughout the house from the sink, which will often save annoyance and damage 25 by being able to shut off the water should a leak occur without the loss of time necessary to reach the main stop-valve.

In the formation of my improved sink I prefer that the bottom thereof shall slope in 30 all directions toward the waste-pipe and that the corners thereof shall all be so rounded as to cause the free flowing off of water and grease, thereby greatly facilitating the cleaning of the sink and improving its sanitary 35 condition.

An important feature of my improvement is that no woodwork is needed for placing the sink, and as this woodwork invariably becomes fouled by constant soaking in of water, 40 grease, and impurities it follows that the use of such wood is objectionable, and when dispensed with the sink is rendered more cleanly and desirable.

My improved sink is especially adapted for 45 use in pantries and the like, since the pipes

may be readily connected therewith and the sink held in place without woodwork or brackets, and when so arranged accumulation of dirt or the harboring of insects is entirely prevented.

Having thus fully described my invention, what I claim as new and useful is—

1. A sink cast in a single piece consisting of bottom, front and side walls, and a back extending upwardly at right angles to the bottom and above the other walls, vertical casings formed on the back to inclose the water-pipes, said casings being cut away from the back near their tops, couplings having flat rear walls, each also having a vertical 60 passage therethrough with a second passage leading from the first-named passage, the ends of the passages being screw-threaded, a downwardly-projecting flange formed on the coupling and inclosing the top of the casing, 65 the top of the casing fitting against a shoulder in the coupling, plugs threaded in the upper ends of the vertical passages, and means for securing the couplings to the back of the sink, as and for the purpose described. 70

2. In a device of the character described, a sink body and back formed together, said back having ways formed therein for inclosing water-supply pipes, the wall at the top of the ways being recessed or cut away to form 75 a shoulder, couplings having flat rear walls fitting in the recess, said rear walls of the coupling being of greater length than the front walls of the coupling, a shoulder formed on the boss at the front of the coupling fitting 80 against the end of the casing, as and for the purpose set forth.

In testimony whereof I have hereunto affixed my signature in the presence of two subscribing witnesses.

WILLIAM LOVE.
